UNITED STATES PATENT OFFICE.

SUNKER ABAJI BISEY, OF NEW YORK, N. Y.

LUBRICATION OF MOLDS.

Application filed October 4, 1922. Serial No. 592,210.

The present invention relates particularly to molds of the character covered in my co-pending application, wherein continuous leads and rules are cast by forcing the molten metal into a mold chamber of the desired shape and continuously withdrawing the product as fast as the metal congeals.

In order that the operation be continuous and uninterrupted it is necessary that the metal in its molten and congealing conditions shall pass into and through the mold chamber without adhering or clinging to the walls of such chamber.

One of the main purposes of this invention is to overcome this tendency of the metal to adhere to the mold walls and to insure the free passage of the finished product.

One of the novel features of the invention by which the foregoing and other objects are attained is the introduction of a lubricating agent into the stream of molten metal on its way to the mold chamber so that at the time the metal enters the mold the lubricant will have dispersed sufficiently to form a film surrounding and in effect "coating" the body of metal.

Other novel features of the invention will appear as the specification proceeds.

The accompanying drawing illustrates but one simple form of the invention, it being understood that the structure may be modified without departure from the true spirit and scope of the invention, hereinafter defined and claimed.

Figure 1 is a broken part sectional plan view showing parts of the melting pot and the mold chamber with the mold lubricator applied thereto.

Figure 2 is a cross sectional view as taken on substantially the plane of line 2-2 of Figure 1.

In the illustration the melting pot is indicated at 5, equipped with suitable pumping mechanism 6 for supplying the molten metal in a substantially continuous stream through the throat 7 to the mold chamber 8.

The mold chamber may be suitably cooled, as by means of a water jacket so as to cause the metal to congeal therein and as the metal congeals and assumes the shape of a final product, such as a lead or rule which is forced or withdrawn from the chamber as by means of cooperating endless drawing chains.

Oil or other suitable lubricating agent is introduced into the stream of molten metal,

in the present disclosure by means of an injector in the nature of a nozzle 10 supplied with lubricant through a suitable connection 11 and having its orifice controlled by a needle valve 12. In the construction illustrated the throat or passage from the melting pot has an angular bend therein and the injector is introduced at the corner of this bend so that the lubricant enters the stream of metal substantially at the center thereof and while flowing in the same direction. Furthermore, by making the nozzle with somewhat abrupt corners, as shown, there is a tendency for the onflowing metal to produce a slight vacuum about the end of the needle valve, which tends to facilitate the flow of lubricant.

The lubricant may be supplied under pressure, as by means of a small rotary pump 13, but the onflowing stream of metal has an injector effect, tending to carry off with it the lubricant released at the tip of the nozzle. To prevent any opposite effect, that is, of the metal working back into the nozzle, the needle valve may be set to reduce the orifice to a point where it will pass the lubricant but will not pass the molten metal.

As the stream of metal flows on to the mold chamber, the lubricant, being lighter, disperses and seeks the outer surface of the stream, forming in effect an envelope contacting the mold walls and enabling the metal in its fluid, semi-fluid, solidifying and solidified states to pass on freely without clinging or "freezing" to the mold walls.

The lubricant introduced in this way thus speeds up the operation, protects the mold and insures a clean cut, sharply defined final product, free of burrs or other imperfections.

While the invention is particularly adaptable to the continuous casting machine of my invention it will be clear from the foregoing that the invention is applicable to intermittent and other forms of casting machines.

What I claim is:

1. The combination with a mold for continuous casting, including a mold chamber with means for supplying a continuous flow of material thereto and for continuously withdrawing the solidified product therefrom, of means for continuously introducing a lubricant into the body of the material flowing to the mold chamber.

2. The combination with a mold for pro-

ducing castings of indefinite length, including a mold chamber with a supply passage leading thereto, of a nozzle introduced into and terminating within said supply passage 5 so as to be surrounded by the flow of casting material and means for injecting a controllable supply of lubricant through said nozzle.

3. In apparatus of the character disclosed, 10 a melting pot, a casting chamber open for the exit of the product shaped therein, a supply passage extending from the melting pot to the casting chamber and a lubricant supplying nozzle entered in and disposed 15 within said passage.

4. The structure of claim 3 in which the passage has an angular turn therein and in which the nozzle is introduced at such turn.

5. In apparatus of the character disclosed, 20 a melting pot, a casting chamber connected therewith and a lubricant supplying nozzle entered into the body of molten metal supplied to the casting chamber and having an orifice discharging in the direction of flow 25 of the molten metal.

6. In apparatus of the character disclosed, a melting pot, a casting chamber open for the discharge of the product shaped therein, 30 a supply passage extending from the melting pot to the casting chamber, means for forcing the molten metal through said passage under pressure, a lubricant supplying nozzle having an orifice at the end of the same discharging into said passage and

means for accurately regulating said nozzle 35 orifice to a size large enough to pass lubricant to the molten metal but too small to permit flow of molten metal into the nozzle.

7. In apparatus of the character disclosed, a mold and means for supplying a flow of 40 material thereto, a lubricant supplying nozzle positioned in the flow of material to inject lubricant into the center of the stream of such material and means for controlling said nozzle to admit lubricant to the material 45 and to exclude material from the nozzle.

8. The herein disclosed process of lubricating molds which includes injecting a lubricating medium into the stream of material flowing to the mold chamber through 50 an orifice and adjusting said orifice to pass the lubricant but exclude the material.

9. The herein disclosed casting process which includes continuously forcing a supply of fluid material to a mold chamber, 55 continuously withdrawing the product from the mold chamber as it takes form therein and injecting a lubricating medium into the body of the material supplied to the mold chamber.

10. The combination with a mold chamber open at one end for the exit of the castings produced therein, of an injector for introducing oil under pressure centrally into the opposite end of said mold chamber. 60 65

In witness whereof, I have hereunto set my hand this 20th day of July, 1922.

SUNKER ABAJI BISEY.
